UNITED STATES PATENT OFFICE.

LEWIS W. HARRIS AND WILLIAM M. PARKER, OF RICHMOND, INDIANA.

BODY-CATCH FOR CASKETS OR THE LIKE.

No. 874,502.

Specification of Letters Patent.

Patented Dec. 24, 1907.

Application filed August 21, 1907. Serial No. 389,457.

To all whom it may concern:

Be it known that we, LEWIS W. HARRIS and WILLIAM M. PARKER, citizens of the United States, both residing in the city of Richmond, in the county of Wayne and State of Indiana, have invented certain new and useful Improvements in Body-Catches for Caskets or the Like, of which the following is a full and accurate specification, being 10 such as will enable others skilled in the art to which the invention relates to make and use the same with absolute exactitude.

Our present invention relates to improved means for detachably securing together the 15 meeting edges of casket bodies and their lids or covers, and the objects of our invention, broadly speaking, is to provide body-catches for caskets or the like which will be strong and durable in construction, easily operated 20 and controlled, which will be pleasing in appearance, and which can be manufactured and sold at a comparatively low price.

More specifically stated our object is to provide catches for caskets and their lids 25 which will be simple in character and which may be inserted and secured in operative position with a minimum amount of time and labor devoted thereto.

Other objects and particular advantages of 30 our invention will be brought out in the course of the ensuing specification, and the particular features which are new will be pointed out in the appended claims terminating this specification.

The preferred manner for carrying out the 35 objects of our invention, and that which in practice has been found to be the most desirable, is shown most clearly in the accompanying drawings, in which

Figure 1 is a central longitudinal section of portions of the side and of the lid of a casket, showing the side and lid separated, and also showing the members of the catches 40 separated. Fig. 2 is the same as Fig. 1 except that the side and top are shown in contact with each other, and the catches are shown in locking engagement with their respective members. Fig. 3 is a plan view of the lower or contact edge of one side of the 45 casket-top, showing the members of the catches secured together. And Fig. 4 is a plan view of the upper edge of one side of the casket.

Similar reference characters denote like 50 parts throughout the several views of the drawings.

In order that our invention may be more fully understood and its advantages be fully appreciated we will now take up a detail description thereof, in which we will set forth 60 the construction and operation of the invention as briefly and as compactly as we may.

Referring to the drawings,—the characters A and A+ denote portions of the head and foot, respectively, of one side of a casket 65 lid or top. And the characters B and B+ denote portions of the head and foot, respectively, of one side of the casket proper. It is to be presumed for convenience of description that Fig. 1 will show one side of a casket, 70 and that Fig. 2 will show the other side of the same casket. The several parts of the catches which are referred to as located on one side of the casket will be designated by certain characters, while like parts which are 75 located on the opposite side of the casket will be designated by corresponding characters primed.

The numeral 1 denotes a plate which is let in flush with the edge of the lid and is permanently secured by a plurality of screws, 80 a—a—a, as indicated. Integral with the forward edge of the plate 1, and extending rearward and downward at an angle therefrom, is a tongue formed by the two substantially half-round members 2 and 3 lying parallel with each other and connected at their outer lower ends by the loop 4. Said loop forms a spring which normally forces the said members slightly apart, as in Fig. 1. Extending forwardly from the upper (free) end of the member 3 is a plate 5, and extending out at right angles from the latter is the finger-hold 6 which is so arranged as to be in reach of the operator at the head of the casket 85 when the casket is closed. In the forward end of the plate 5 is a segmental notch 90 5^a, as shown in Fig. 3, for the purpose herein-after set forth.

Extending down through the edge of the 100 side B is an aperture, formed on same angle as is said tongue, in which is fitted the thimble 7. Said thimble is formed from a single piece of sheet metal rolled into the form of a tube with its edges unconnected whereby the 105 diameter of the thimble may be varied somewhat and by which it may be caused to neatly fill the said aperture therefor by the resiliency of the material of which the thimble is formed. The upper end of said thimble is formed on 110 an angle whereby it will correspond with the upper edge of the side B. Extending forward

from the thimble 7 is a plate 8, which is parallel with and let in flush with the upper edge of the side B as shown. The plate 8 may be secured by the screw 9.

5 The numeral 10 denotes a tooth which is struck up from the plate 8 and faces rearwards and is so positioned as to engage the notch 5^a when the lid is secured, as in Fig. 2.

10 The numeral 11 denotes a plate which is let in flush with the edge of the lid where it is secured by a plurality of screws, b—b—b, as shown. Formed integral with the rear edge of the plate 11, and extending rearwards and downwards at an angle therefrom, is a tongue 15 formed by the two substantially half-round members 12 and 13 lying parallel with each other and connected at their outer lower ends by the loop 14. Said loop forms a spring which normally forces the members 12 and 20 13 slightly apart.

Extending down through the edge of the side B + is an aperture which is formed on same angle as is said tongue, in which is fitted the thimble 17. Said thimble is formed from 25 a single piece of sheet metal rolled into the form of a tube with its edges so formed that the diameter of the tube may be varied and by which it may be caused to neatly fill the aperture therefor. The upper end of said thimble 30 is formed on an angle whereby it will correspond with the upper edge of the side B +. Said thimble is retained in its aperture by the expansive resiliency of the material of which it is formed.

35 The operation of our invention is very simple.—If for instance the casket employed be provided near its forward end with the devices shown on the left in the several views of the drawings, one complete device being 40 located on each side; and that the casket be provided near its foot-end with the devices shown on the right in the several views of the drawings, one complete device being located on each side. The lid which carried the male 45 members of the several catches may now be brought over the casket which carries the complementary female members of said catches. First placing the lid a little forward of its final operative position, to enter the 50 tongues into their respective thimbles 7, 7', 17 and 17'. Now by allowing the lid to assume its normal operative position it is apparent that it will move downward and rearwards, and when the lid contacts with the 55 upper edge of the casket proper then the teeth 10 and 10' will have pressed up the respective plates 5 and 5' and said teeth will have entered the respective notches in the

ends of the plates 5 and 5' thereby allowing the said plates to spring down each into engagement with its respective tooth 10 and 10' which will, manifestly, lock the lid positively in position as shown in Fig. 2.

If it be desired to remove the lid then the operator has only to lift up on the finger-lifts 65 6 and 6' which will release the plates 5 and 5' each from its respective tooth 10 and 10' which will allow the lid to be moved upwards and forwards from connection with the body of the casket.

Having now fully shown and described our invention and the best means for its construction and operation to us known at this time, what we claim and desire to secure by Letters Patent of the United States, is—

75 1. Body catches for caskets or the like, comprising a plurality of devices each comprising male and female members connected to the lid and the upper edge of the casket respectively, the male member composed of a 80 plate secured to the lid, two half-round members integral with the plate and connected at their outer end by a spring loop and disposed at an angle to the lid, the female member comprising a tube fitted in an aperture therefor in 85 the edge of the casket and disposed at an angle corresponding with the angle of said tongues, a spring catch for the two forward devices to lock the lid in position, and means for releasing said catches when the lid is to be 90 removed, all substantially as shown and described.

2. Means for securing casket-lids on caskets, a plurality of thimbles disposed at an angle in the edges of the casket, a tongue for 95 each of said thimbles, said tongues being formed of two substantially half-round portions connected integrally by a loop, one of said members of the tongues being secured to the lid and the other being free to move, a 100 plate carried by the free end of two of said tongues, a finger-hold extending out from each of said two plates, and a tooth to engage each of said plates, said teeth being rigidly connected to the casket body, all substantially as shown and described and for the purposes set forth.

In testimony whereof we have hereunto subscribed our names to this specification in the presence of two subscribing witnesses.

LEWIS W. HARRIS.
WILLIAM M. PARKER.
